UNITED STATES PATENT OFFICE.

FREDERICK A. WINTER, OF THOMSON, GEORGIA.

CARTRIDGE-LOADING MACHINE.

SPECIFICATION forming part of Letters Patent No. 289,592, dated December 4, 1883.

Application filed May 16, 1883. (No model.)

To all whom it may concern:

Be it known that I, FREDERICK A. WINTER, of Thomson, county of McDuffie, Georgia, have invented a new and Improved Cartridge-Reloading Machine, of which the following is a full, clear, and exact description.

My invention consists of an intermittently-rotating horizontal disk containing cells for holding the cartridge-shells for filling them, with which disk I have contrived a novel feeding device for shifting it around as the cartridges are charged; also, a device for pressing in the wads and shot or bullets, as the case may be; and my invention also consists of attachments, in connection with the recharging mechanism, for crimping the cartridges when paper cartridges are used; also, attachments for capping and attachments for uncapping the cartridges, and also an attachment for holding the powder and shot flasks, in connection with the cartridge-holding disk, for convenience in manipulating them to charge the cartridges, all as hereinafter fully described.

Reference is to be had to the accompanying drawings, forming part of this specification, in which similar letters of reference indicate corresponding parts in all the figures.

Figure 1 is a side view of my improved machine partly in side elevation and partly in section. Fig. 2 is a horizontal section on the line *xx* of Fig. 1. Fig. 3 is a detail in sectional elevation on the line *yy* of Fig. 2, showing the method of crimping the paper shells. Fig. 4 is a section on line *zz* of Fig. 3, also illustrating the method of crimping the cups. Fig. 5 is a section of the feeding-ratchet and removable pivot of the cell-disk. Fig. 6 is a detail of the feeding-pawl in side elevation. Fig. 7 is a perspective view of the flask-holding attachment, and Fig. 8 shows an attachment for seating bolts.

On any suitable base, *a*, I arrange a disk, *b*, of wood or metal, as preferred, to turn on a center-pivot, *c*, said disk having a series of holes, *d*, bored through it from side to side in a circle around the margin, to form cells in which to set the cartridge-shells *e* (dotted) upright to be reloaded, the said shells resting on the surface of the bed-plate *a*, which has an annular rabbet, *f*, under the cells of the disk

to allow the shells to rest sufficiently low in the disk, and a circular groove, *g*, is provided in the face *f* for the caps *h* of the cartridges to run in, so as not to be exploded by the friction they would be subject to in case they were 55 allowed to rub on the surface of the bed-plate.

Cartridges *e*, that are used by firing the charges from them and reloading them for subsequent use, for which the machine is mainly intended, also paper and other cartridges to be 60 filled, are placed in the cells and charged with powder, shot, or balls and wads. They are then to be shifted under the wad-rammer *i* in succession. When the wads are properly 65 pressed down by the lever *j*, to which the rammer is attached, the rammer being arranged in a guide-hole, *k*, in the foot of the arch *l*, consisting of two parallel beams attached at each end to a foot, *m*, resting on a vertical support, *n*, rising up from the base-plate. The lever *j* is 70 arranged between the two members or beams of the arch for guides, and is pivoted at *o* to a bracket, *p*, of a center post, *q*, suspended between the beams of the arch over the center of the disk to hold the upper end of the vertical 75 pivot *e*, around which the disk turns. Besides working the wad-rammer, the lever *j* is also employed to shift the disk around successively by the teeth *s* of a crown-wheel *t*, located on the disk, and the pawl *u*, attached to the lever. 80 To enable the lever *j*, which works vertically to operate the wad-rammer, to turn the disk horizontally, the teeth *s* are pitched obliquely on the upper face of the crown-wheel, so that the point of the pawl moving radially through 85 the spaces between them, and acting on one of the inclined sides of one of said teeth, will force the disk around. The teeth are also pointed at the inner ends, so that the pawl, being jointed at *v*, will swing past the points for passing from 90 one tooth to another. The joint *v* is shouldered at *w*, so that when the lever *j* is shifted upward to withdraw the wad-rammer, the pawl *u*, swinging outward between the teeth of the crown-wheel, will shift the disk to the right 95 hand, and when the lever *j* is thrust down to force down the rammer the pawl will turn on its pivot *v* and swing back over the tooth into the next groove preparatory to shifting the disk again on the next rise of the lever *j*. 100

The pawl u is secured to the lever j by a clamp-bolt, x , having a flat-sided shoulder, y , in the slot z of the pawl, to prevent the latter from turning, and the slot allows the pawl to be shifted up and down for setting it with relation to the teeth s .

- For enabling the cell-disk to be taken out readily and others to be put in having cells of different sizes for cartridges of different sizes, the center pivot, c , has a flat head, a' , with a curved edge, b' , and is fitted in a correspondingly-shaped groove in one side of the post q , where it is secured at its upper end by the ring c' , which slides up on the lower end of the post, fitting snugly thereon, and also fitting the outer edge of the head a' , so as to hold it securely in the post. The ring c' is slipped down from the end of the post on the wheel t , as indicated by the dotted lines, when the pivot is to be removed. The lower end of the pivot is fitted in a step, d' , in the bed-piece, to which a sloping groove, e' , leads in the radial plane of the groove in the post for the head of the pivot to facilitate the placing of the pivot in position. A spring-stop, f' , is arranged to catch in notches or holes in the periphery of the disk to stop and hold it in the right position for the rammer to enter the cartridge.
- I propose to provide the rammer-rod i with interchangeable ends i' i'' , as shown in Figs. 1 and 8, and in different forms, as required, for ramming pistol or rifle cartridges with balls, which may be charged in this machine as well as shot-cartridges to be rammed with wads, the machine being adapted by the use of disks with cells of proper size and different forms of rammer-heads to load or charge any kind of shell that is reloadable.
- On the opposite side of the machine I have arranged devices for crimping paper shells, capping and uncapping shells, as follows: At g' is an upright stud adapted to set up the paper shells by inverting them and placing the open end down on the stud. Said stud is fixed on a pivot, h' , whereon it may swing down to lay the shell in the crimping-die i' , over which is another die, j' , in a lever, k' , pivoted to the bed-die i' at l' to be swung down on the shell to crimp it, as seen in Figs. 3 and 4, by the ribs m' of said dies. The stud g' swings back to its upright position on its pivot h' to receive the cartridges more readily than if lying down in the dies. It has an extension, n' , down the side of the base o' , to prevent it from swinging back too far and straining the pivot, and also to maintain it more substantially in its upright position.
- For recapping the cartridges, I have provided the socket-holder p' , under the lever k' and in front of the crimping-dies in which the cartridges are to be placed bottom up, with a cap set at the hole in the bottom wherein the cap is to be pressed, so that the crimping-lever k' may also be used, by swinging it down on the cap, to force it into the cartridge; and

to utilize the same lever for uncapping, I have provided it with a pusher, q' , that may, when required, be swung down and dropped into the cartridge when said cartridge is resting in socket p' , with its bottom down, to press out the cap by springing the bottom of the cartridge down, as represented in dotted lines, Fig. 3, to cause the cap to fall out and escape through the hole s' in the bottom of the socket p' . To connect this pusher with the lever k' , so as to remain with it when not in use without interfering with the use of the lever for crimping and capping the shells, I have recessed the front or under side of the lever from t to t' for a space in said lever to lay the pusher and connected the pusher to pivot-studs w' by the wire loops v' , which project into recesses w' in the sides of the lever and hold the pusher up along with the lever when the pusher is not to be used; but said wire loops allow the outer end of the pusher to be sprung out of the recess t' , to pull said loops out of the recesses, which allows the pusher to swing down and drop into the cartridge-shells to push out the caps, as before stated.

I propose to pivot the powder-charging flask a^2 , and the shot-charging flask b^2 , upon the wire supports c^2 , which are suspended on the top of the post q , the wire supports being extended down to such proximity to the cartridge-shells that they may be charged from the flasks by tilting up said flasks and pouring the powder and shot into the cartridges while placed in the disk b .

In practice there will be a slide-door in the bottom of the machine to let the shells drop out when loaded, and the rammer-rod i will have a spring to hold it up when not in use.

Having thus described my invention, I claim as new and desire to secure by Letters Patent—

1. The combination, in a cartridge-loader, of the intermittently-rotating cell-disk b , base a , and a rammer, i , the said cell-disk being arranged on the vertical pivot-stud c , stepped in the base a , and said base having the cap-groove g , substantially as described.

2. In a cartridge-loader, the combination of the crown-wheel t , supported on suitable bearings, having pointed and oblique teeth s on its upper surface, and the lever j , pivoted to the upright post q , having the rammer i , and the feed-pawl attached to it, the said pawl and crown-wheel teeth being arranged in relation to each other, whereby the lever working vertically to actuate the rammer turns the disk horizontally, as described.

3. In a cartridge-loader, the vertically-operating lever j , pivoted to the upright post q , jointed feed-pawl u , attached thereto, and the obliquely-toothed horizontal feed-wheel t , suitably supported, combined, and arranged, substantially as hereinbefore described, to feed said wheel horizontally by the vertically-working lever.

4. In a cartridge-loader, the combination,

with the feed-wheel *t*, suitably supported and provided with oblique teeth *s*, and the lever *j*, pivoted to the post *q*, of the jointed pawl *u*, adjustably secured to the said lever, and having shoulder *w* at its joint, substantially as herein shown and described.

5. In a cartridge-loader, the combination, with the tilting cartridge-stud *g*, of the crimping-dies *i j*, provided with the crimping-ribs *m*', and the lever *k*', substantially as herein shown and described.

6. In a cartridge-loader, the combination of the socket *p*', provided with the aperture *s*' in its bottom, and arranged in front of the crimping-dies, the lever *k*', carrying one and pivoted to the bed-piece of the other of said dies, and the push-rod *q*', pivoted to the lever *k*', above the cartridge-supporting socket, whereby the latter lever may be operative for uncapping, capping, and crimping the cartridge, substantially as herein shown and described.

7. In a cartridge-loader, the combination, with the crimping-lever *k*', arranged to project over the cartridge-socket *p*', and provided with the recess *t* on its under side, the side recesses, *w*', and the pivot-stud *u*', of the uncapping-pusher *q*', provided with the loops *v*', fitting into the side recesses and over the pivot-pin, substantially as herein shown and described, whereby the pusher can be held to the crimping-lever when not in use, as set forth.

8. In a cartridge-loader, the combination, with cartridge-holding disk *b* and center post, *q*, of the supports *c*', secured to said center post, and the charging-flasks *a*' *b*', pivoted between said supports, substantially as herein shown and described.
